UNITED STATES PATENT OFFICE

HARRY M. HENDERSON, OF WASHINGTON, DISTRICT OF COLUMBIA

GRADER FOR VENDING-MACHINE CHECKS

Application filed February 4, 1929. Serial No. 337,378.

This invention relates to new and useful improvements in sorting or grading devices, and particularly to devices for grading the checks used in vending machines.

5 In vending machines, such as those which sell merchandise, and those which render telephone service, coins are deposited within the machines for the purpose of operating the machine. Unscrupulous persons, who 10 seek to obtain something for nothing, resort to the use of slugs which have the size and shape, and the approximate weight of the proper coins necessary to successfully operate the machines. Thousands of dollars are 15 lost, to the owners of the machines, by the use of these slugs.

It is the principal object of the present invention to provide a device whereby these slugs may be graded, in accordance with 20 their size, shape, and magnetic qualities, as well as weight, so that slugs which do not measure up to the proper qualification will be returned to the depositor, before they can enter the machines.

25 Another object is to provide a device of this character which is adapted to be used in connection with any of the vending machines now in use.

Other objects and advantages will be apparent from the following description when taken in connection with the accompanying drawings.

In the drawings:

Figure 1 is a perspective view of the device in assembled condition.

Figure 2 is a vertical sectional view on the line 2—2 of Figure 1.

Figure 3 is a vertical sectional view on the line 3—3 of Figure 1.

40 Figure 4 is a transverse sectional view on the line 4—4 of Figure 1.

Figure 5 is an elevation of a portion of the device, certain parts being shown in dotted lines.

45 Figure 6 is an elevation of the plate which carries the weighting means.

Figure 7 is an elevation of the reverse face of the plate which carries the magnet.

50 Figure 8 is a perspective view showing all of the plates in position to be assembled.

Referring to the accompanying drawings, and especially to Figure 8, it will be seen that the device is made up of a series of plates, designated by the letters A, B, C, C', and D, which are assembled in the manner shown in Figure 1, and secured together by means of the screws or bolts 10. It will be noted, however, that the plates C and C' are secured together, so that they form a unit, for a purpose which will appear later herein. The upper end of the plate A is formed with an integral reduced neck portion 11, while the plates B and C have similar neck portions 12 and 13, respectively, all of said neck portions being of the same width, as clearly seen in Figure 1, it being noted that the neck portion 11, of the plate A is slightly shorter than the other neck portions, and has its upper end formed with a downwardly curved face 14, and a recess 15, in its inner face, opening upwardly through the upper end thereof, such recess being approximately one-half of the thickness thereof, and corresponding to the thickness of the proper coin for operating the machine with which the device is to be used. In the inner face of the plate A, adjacent one vertical edge thereof, there is formed a longitudinal recess 16, the upper portion of which is of approximately twice the depth of the lower portion, as clearly seen in Figure 8, the lower end of said recess opening through the bottom of the plate, for discharging the slug, as shown at 16', and as will be explained later herein. The neck portion 11, of the plate A, has an opening therethrough, as shown at 17, to permit the introduction of the finger of the operator for the purpose of pushing the check inwardly from the recess 15, so that the check will fall through the device, to be properly graded.

In the neck portion 12, of the plate B there is formed a circular opening 18, which is just enough larger than the proper coin or check, to permit such coin or check being easily passed therethrough. Also formed through the plate B, adjacent the vertical edge opposite to that of the recess 16, of the plate A, is an angular opening 19, the lower

wall of which is beveled, as at 20, on the face of the plate which bears against the plate A, while the upper wall is beveled on the opposite face of the plate. This opening is provided to permit slugs or coins of the proper size to readily pass therethrough. The other face of the plate B is cut out to form a large recess 21, the upper end of which communicates with the opening 18, by means of a passage 22, whereby a coin or check passed through said opening 18, will fall down through said passage into the large recess. The lower portion of the recess 21 has an outlet channel 23, which is directly below, and in a vertical line with, the passage 22, for the passage of checks which have been graded and found undesirable, and lacking one or more of the requirements necessary to operate the machine. In the approximate center of the recess 21 there is formed a boss 24, whose thickness is equal to that of the depth of the recess, and pivotally mounted in the recess, on the pin 25, is an L-shaped member 26, having the attenuated finger 27, and the heavier depending portion 28. The upper face of the boss 24 is formed with a recess 29 which receives the said finger, when the member 26 is overbalanced by a coin or check of the proper weight falling thereon. The upper face of the boss 24, beyond the recess 29, and adjacent the angular opening 19, is formed in an inclined plane which forms a continuation of the upper face of the finger 27, when said finger lies within the recess 29, whereby to form an inclined runway for the check to roll to said opening 19, when said member 26 is overbalanced by a check. Checks which are not heavy enough to cause the member 26 to be overbalanced so that the finger 27 moves into the recess 29, will roll toward the weighted end of the member, by reason of the fact that the upper face of the finger is formed with a slight elevation, shown at 30, toward the free end thereof, and the shoulder 31, of which lies directly below the center of the passage 22, so that when a check drops from the passage 22 it will fall on the said shoulder. If the check is of the proper weight it will tilt the member 26 and roll down the finger 27, whereas if it is too light, the member 26 will not be tilted to a degree to permit the rolling of the check, as above mentioned; but such check will roll down the member 26 toward the weighted end, and drop therefrom, whereby to follow the adjacent side wall of the large recess 21, and finally be discharged through the outlet channel 23, outside of the machine. Thus a check is stationary, in balanced position on the shoulder 31, for an instant, so that the weight of the check can be properly determined, such check completely tilting the members 26, if of the proper weight, and rolling off the outer end of the finger, or, if not of the proper weight,

failing to tilt the member, and rolling off in the other direction. Thus the check is graded according to weight, as it passes through the device, such check falling into the machine to cause the operation thereof, if of the proper weight, or being discharged from the machine, if it is not of the proper weight.

The member, or plate C—C', has formed in the face which bears against the plate B, in covering relation to the recess 21, a vertical elongated recess 32, such recess being formed wholly through the plate C, and in the plate C', in opposition to the recess or opening 32, and in the inner wall thereof, there are formed openings 33. In the opposite face of the plate C' there is formed a recess 34, of a size and shape to properly receive the horseshoe magnet 35, the ends or poles of such magnet being arranged in covering relation to the openings 33, whereby such magnet may attract any magnetic slugs which may fall on the tiltable member 26. The recess 21 is of approximately the depth, corresponding to the thickness of a proper check, and the recess 32 is of the same depth, so that when a check formed from magnetic metal rests for an instant on the member 26, the time elapsing being sufficient to permit the magnet to attract the check out of the recess 21, into the recess 32, so that the check may drop to the lower end of said recess 32, and be deflected off the beveled face 36, at said lower end, to be ultimately discharged through the outlet channel 23. Formed on the face of the plate C—C', in which the magnet is seated, and at one side of said magnet, is a casing 37. Formed through the plates C and C', directly opposite the angular opening 19, is a vertical elongated, and comparatively narrow slot 38, and pivotally mounted in said casing 37, is a weighted member 39, the upper forward end of which is formed with a pair of vertically aligned projections 40 and 41, which extend through the said slot 38 for engagement by a check falling past said slot 38 and opening 19. This member is provided to take care of slugs which have openings in their centers. When a check, in the form of a washer having a central opening, and being of the proper thickness, diameter and weight drops on the member 26, such check will cause the tilting of such member, whereupon the check will roll off the end of the finger 27, and as it passes the slot 38, the advanced edge of the check will engage the lower projection, which extends beyond the face of the plate, so that the member 39 will be rocked, and the upper projection 40 pass into the opening of the check. The check will hang on the projection 40, whereby to continue the rocking of the member 26, until the check drops from said projection, into the recess 21, and thence out through the opening 23. Thus the check is permitted to fall past the slot 38, and out

through the outlet channel 23, thereby not entering the vending machine. If, however, the check is not provided with a central opening, its weight on the lower projection 41, will cause the rocking of the member 39, with the result that the upper projection 40 will push the check through the opening 19, so that the check will be deflected into the proper channel to pass out of the outlet 16'. 5

10 The plate D is formed with a slot 42 through which the casing 37 passes, when all of the plates have been properly assembled, and secured together, such plate D serving to hold the magnet within its recess.

15 From the foregoing it will be seen that when a slug is inserted in the upper end of the recess 15, the check will drop to the bottom of such recess and remain there, until the operator inserts his finger in the opening 17, and pushes the check into the upper end of the passage 22, whereupon the check falls upon the shoulder 31. If the check is of the proper weight, for the successful operation 20 of the machine with which the device is used, the member 26 will be overbalanced so 25 that the finger 27 will be swung downwardly into the recess 29. The check will then roll down on the upper face of the elevated portion 30, and the inclined portion of the boss 24, until it abuts the adjacent wall of the recess 21, and lies opposite the opening 19, when said check will engage the projection 41, of the member 39, causing said member 30 to be rocked on its pivot, whereupon the upper projection 40 will push the check 35 through the opening 19, into the recess 16, from whence it escapes from the device by way of the lower open end 16' of said recess, and into the machine to be operated.

40 Should, however, the check have a central opening, its weight upon the member 39 will permit the upper projection 40 to pass into the opening of the check, so that the check will fail to pass through the opening 19, but 45 will escape by way of the outlet 23. If the check is too light to tilt the member 26, such check will roll off the weighted end of said member and escape through the outlet 23. If the check is of iron, steel, or other magnetic material, and is of the proper diameter 50 and thickness, its momentary pause on the shoulder 31 will be sufficient to permit the magnet to draw such check out of the recess 21, into the recess 32, whereupon the check 55 will fall down and be deflected by the beveled face 36, into the outlet channel 23, and out of the machine. Checks which fall through the opening 19, into the recess 16, are of the proper weight to operate the machine, and 60 will fall from the lower end of said recess 16, into the proper coin receptacle, within the machine, not shown.

The first test of the check is for thickness, as the check must be of the proper thickness 65 to pass into the upper end of the recess 15.

The second test is for diameter, which is made when the operator inserts his finger in the opening 17 and pushes the check from the recess 15 so that it may pass through the opening 18. The third test is for weight, 70 which is made when the check falls upon the weighing member 26. If the check has an opening therein the member 39 will act upon the check to cause the latter to pass through the device, and be returned to the operator. 75 The same means which acts upon the apertured check to cause the same to be returned to the operator serves to deflect the check of proper dimensions and weight to the machine with which the device is associated. The test 80 as to material is accomplished by the horseshoe magnet. If the check is of magnetic metal it will be attracted by the magnet and deflected into a channel which will ultimately discharge the check from the device. Thus, 85 practically all checks of an undesirable nature, and which will not successfully operate the machine, will be discarded.

What is claimed is:

1. A device for grading vending machine 90 checks comprising a weight testing lever on which a check is adapted to fall for imparting an initial rocking movement to the lever, means on the rocker for engagement with the check to prevent further movement or return movement of the rocker until the weight of the check determines the direction in which said rocker will rock, and means for determining the fall of the check and thereby the impact thereof against said lever. 95

2. A device for grading vending machine 100 checks according to weight including a member having a check receiving opening, a rocker beneath the opening having a finger provided with an intermediate shoulder on which the check is adapted to fall, said rocker being arranged to be rocked if the check is of the proper weight whereby said check will roll along said finger, said check being adapted to roll in the opposite direction if of improper weight, and a stop for engagement by said finger under the weight of the check, said stop forming a continuation of a runway formed by said finger. 110

3. A device for grading vending machine 115 checks comprising a weighted rocker on which a check is adapted to fall to impart an initial rocking movement to the lever, a shoulder on the lever on which the check falls and which holds the check against rolling movement in either direction on the rocker until the weight of the check determines whether the rocker shall continue its rocking movement to discharge the check in one direction or resume its normal position to discharge the check in another direction, and means comprising a check supporting ledge for governing the fall of the check. 120

4. A device for grading vending machine 130 checks comprising a member having a re-

cess and an opening for passing a check into the recess, and a weighted rocker mounted beneath the opening, said rocker having a shoulder on which a check falls from said opening to give an initial rocking movement to the rocker, whereupon the check will rest against said shoulder until the weight of the check determines whether the rocker will continue its rocking movement and discharge the check in one direction, or resume its normal position and discharge the check in another direction.

In testimony whereof, I affix my signature.

HARRY M. HENDERSON.
